BAIT RECEPTACLE

Howard S. Ross, Beverly Hills, Calif.

Application August 24, 1945, Serial No. 612,406

3 Claims. (Cl. 43—55.)

1

This invention relates to a bait receptacle, and more particularly to a receptacle for holding various types of earthworms used as bait.

The various types of earthworms used by fishermen as bait are generally stored with a mass of earth in a container until used. As the upper portion of the earth within the container tends to dry out, the worms invariably will form in a mass at the bottom of the container, where the earth is more moist. A fisherman therefore is forced to either jostle the container in an attempt to force the worms to the top, or to actually spread the earth with his hands to reach the worms at the bottom of the container.

It has been heretofore proposed to furnish a container suitable for holding earthworms with a rake device which would actually rake the worms from the bottom of the container and draw them to the top. This device was objectionable for it tended to cut and shred the worms. Thus, after the device was operated several times, the majority of the worms were mutilated and their efficiency as bait decreased.

The present invention obviates the difficulties previously had in storing live earthworms for the container in which the worms are stored is so mounted that either end of the same may be moved to an upper position relative to the other end. In the now preferred embodiments of the invention, the container is open at the one end thereof and a cover mounted by a spring pressed hinge normally closes the open end of the container. The container is so mounted that it is normally supported in an inverted position with the open end thereof lowermost. Thus, even though worms do work their way to the lowermost portion of the container, they are readily accessible when the container is swung to move the open end thereof to the uppermost position.

In one embodiment of the device of the present invention the container is adapted to be supported by an article of clothing, such as the belt, of the user. The container is pivotally mounted on the belt engaging member, and as the pivotal axis is located adjacent the closed end of the container and is displaced laterally from the center of gravity of the same, the container will normally swing to a position in which the open end closed by the cover is lowermost. As the container is normally supported in an inverted position, the worms, although they do work down into the moist earth, will nevertheless be readily accessible when the container is swung upwardly to bring the open end thereof to an uppermost position.

2

To prevent the container from rocking about the pivotal axis as the user moves about, the belt engaging means by which the container is pivotally supported is formed with a resilient catch or latch member which engages the cover when the container is moved into its normal inverted position. The latch member not only holds the container against movement relative to the support, but also augments the action of the spring of the hinge by which the cover is mounted to the container.

When it is desired to remove a worm from the container, the latch member is released and the container is rocked upwardly until the cover can be swung back to an open position. It is not necessary to hold the container in the position in which the open end is uppermost, for means are provided for supporting the container in this position. The means are so located relative to the pivotal axis that when the container is upended, gravity holds the container against the supporting means.

In another embodiment of the present invention, the container is pivotally mounted on a stanchion which can be supported on any relatively flat surface. The pivotal axis in this embodiment of the invention is also so located relative to the center of gravity of the container that it will normally be disposed with the open end thereof in a lowermost position. A latch member carried by the stanchion engages and holds the container against movement relative to the stanchion when the container is in its normal inverted position so that the device can be carried by a user without objectionable rocking movement of the container.

As the container can be easily released from the latch member and then swung to present the end closed by the cover as in the earlier described embodiment of the invention, worms which will have tended to work to the lowermost position of the earth will be readily accessible when the cover is swung back to expose the open end of the container.

The stanchion is formed with a support for engaging the one end of the container to support the same in the vertical position in which the open end is uppermost. The disposition of the center of gravity of the container is such that gravity will here again hold the container against the support when it is swung upwardly to bring the open end into an accessible position.

Other features and advantages of the present invention will be apparent from the following de-

scription taken in connection with the accompanying drawings in which:

Figure 1 is a side view of one form of the container of the present invention showing in solid lines the container in its normal inverted position and showing further in broken lines the position of the container when it is moved into the position in which the open end thereof is accessible;

Figure 2 is a front view of the container of the present invention;

Figure 3 is a perspective view of the container shown in Figures 1 and 2; and

Figure 4 is a view similar to Figure 3 but showing in smaller scale a modified form of the device of the present invention.

The bait receptacle of the present invention, referring now to the drawing, and particularly Figure 1 thereof, comprises a container or receptacle 10 of any material suitable for storing moist earth. In the illustrated embodiment of the present invention the container 10 is formed at one end with a semi-cylindrical wall 12 the purpose of which will be hereinafter more fully explained. The container is open at the end opposite to the wall 12 and this end is adapted to be closed by a flanged cover 13 mounted by means of a spring-pressed hinge 14 attached to a wall of the container adjacent the open end thereof. The spring 14a of the hinge 14 normally holds the cover 13 against the open end of the container, but allows the cover to be swung back when desired.

In the form of the invention shown in Figures 1, 2, and 3, the container is pivotally mounted between a pair of ears 15 carried by one leg of a U-shaped clip member 16 adapted to be mounted to the belt of a fisherman or to some other convenient portion of his clothing. The container is pivotally mounted between the ears 15 by suitable pivot pins 17 which may comprise small flat-headed rivets fixed to opposite walls of the container and loosely mounted in aligned apertures formed in the ears 15.

It will be noted that the axis of the pivotal connection between the container and the ears is disposed intermediate the belt or clothing engaging portion of the clip 16 and a vertical line passing through the center of gravity of the container and is located closely adjacent the closed end thereof. Thus, when the container is moved to a position in which the center of gravity is displaced to the right of the pivotal axis, the container will be moved by gravity into a position in which the open end of the container is lowermost. The function of the wall 12 of the container should now be obvious and it will be seen that as the wall is semi-cylindrical, the container can be positioned closer to the supporting clip 16 than would be possible if the end wall was substantially normal to the side wall of the container.

To prevent the container from swinging when the fisherman or user is in motion, the clip 16 is formed with an elongate finger 18 having at the lower edge thereof a detent or hook member 19 adapted to ride over the flange of the cover 13 and outer surface of the latter when the container is swung downwardly into the position shown in full lines in Figure 1. It will be seen that the finger 18 and its detent 19 form a latch member which will not only hold the container against accidental movement relative to the clip, but will also augment the action of the spring hinge and prevent the cover 13 from being moved

back from the open mouth of the container 10.

As the container is normally held in the inverted position shown in Figure 1, worms held by the container as they tend to work down into the moist earth at the lowermost portion thereof, can be readily removed from the container when the same is swung upwardly to move the open end of the same to an uppermost position. This obviates the difficulty had in previous bait containers, where it was difficult to remove a worm from the container due to the fact that the worms worked down into the moist earth at the bottom of the container. To obviate the necessity of holding the container when it is swung upwardly to the position shown in broken lines in Figures 1 and 3, the clip 16 is formed with a support 20 for engaging and supporting the semi-cylindrical wall 12 of the container. The support 20 may be conveniently formed by partially lancing a substantially rectangular piece from the one leg of the clip 16 and then forming the partially lanced piece into a curved shelf-like support adapted to partially embrace the semi-cylindrical end of the container.

It will be seen that when the container is swung upwardly to the position shown in broken lines in the figures referred to above, the center of gravity of the container is moved to the opposite side of the said pivotal axis. This shifting of the center of gravity, as should be understood, results in gravity tending to hold the container against the support 20.

If desired, means may be provided for more positively holding the container 10 in the upright position, and although this means may take different forms, in the embodiment of the invention illustrated this means comprises a ball detent 21 which is adapted to ride into a circular depression 22 formed in at least one of the ears 15. The material of the ears 15 is sufficiently resilient to permit the detent to move into locking engagement with the depression 22.

In an alternate form of the device of the present invention, referring now to Figure 4, a container 23 is pivotally mounted by means of pivot pins 24 between a pair of ears 25 carried by a stanchion member 26. The container 23, as in the earlier described embodiment of the invention, is so mounted between the ears that it will normally swing to a position in which the open end thereof is facing downwardly.

In the preferred form of this embodiment of the present invention the stanchion member, including a pair of oppositely directed pedal members 27, and the ears 25, are fabricated from a single piece of sheet metal stock. It will be seen that the stanchion 26 and its pedal members 27 permit the container 23 to be supported on any flat surface such as the floorboards or a seat of a boat.

The container 23 is provided with a cover member 28 hingedly connected to the same through a spring pressed hinge 29 such as described in connection with the earlier form of the device. The container 23 is held against accidental swinging movement when in its normal inverted position by a resilient finger 30 partially lanced from the stanchion 26 and formed at the outer end thereof with a detent or hook member 31. The resilient finger 30 and its detent 31 serve the same function as the finger 18 in the embodiment of the invention illustrated in Figures 1 to 3 inclusive.

To permit the device to be more readily carried, the pivot pins 24 are formed with suit-

able openings for receiving the opposite ends of a bail 32. The ends of the bail are pivotally mounted within the openings formed in the heads of the pivot pins 24 so that the bail can be swung down against the stanchion 26 so as not to hinder movement of the container 23 when it is desired to expose the end closed by the cover.

As in the earlier described form of the invention, the container 23 is formed with a ball-like detent 33 adapted to be engaged in the circular depression 34 formed in at least one of the ears 25 of the stanchion member. The detent 33 will augment the action of gravity and more positively hold the container 23 in the position in which the cylindrical wall thereof is engaged by the shelf-like support 35 carried by the stanchion member 26.

The container 23 in the embodiment of the invention shown in Figure 4 is intended to be of a larger size than that provided in the form of the device shown in Figures 1 to 3, although for the purpose of illustration it has been shown as similar in size. This embodiment of the invention is intended to be used in the same manner as the embodiment earlier described. It will be seen that the present invention obviates the difficulties had in storing live earthworms for bait as it provides a container which will be normally held in an inverted position so that the worms which will have worked down into the moist earth of the lowermost portion of the container will be readily accessible when the container is swung to an upright position in which the cover member may be moved back to expose the open end of the container.

Although the now preferred embodiments of the present invention have been illustrated and described herein, it is to be understood that the invention is not to be limited thereto, for it is susceptible to changes in form and detail within the scope of the appended claims.

I claim:

1. A bait receptacle of the type described comprising: a clip adapted to be attached to the clothing of an angler; a pair of ears carried by said clip at opposite margins thereof; a container open at one end and including a cover for closing said open end; means for pivotally mounting said container between said ears; means carried by said clip cooperative with means carried by said container for holding said container in a position in which said open end is uppermost; and means carried by said clip, separate from said last named means, adapted to engage said cover when said container is moved to a position in which said open end is lowermost for holding said cover in closed position and said container against accidental movement relative to said clip.

2. A receptacle for storing in a mass of earth angle worms which normally seek the lowermost region of a storing receptacle comprising: a container open at one end thereof; a cover member for closing said open end; a support; means for mounting said container on said support for swinging movement so that said container can be swung to a normal position in use in which

said open end is lowermost whereby the worms within the earth or the like held by said container will seek the lowermost portion of the same adjacent said open end; means for engaging said cover member when said container is disposed in its normal position with the open end thereof facing downwardly for holding said cover member against accidental opening movement; and means for holding said container in a position in which said open end is uppermost when said container is swung thereinto so that said cover member may be moved to uncover said open end and permit removal therethrough of a worm from the earth held by the container contiguous to the open end thereof.

3. A receptacle for storing in a mass of earth angle worms which normally seek the lowermost region of a storing receptacle comprising: a container open at one end thereof; a cover member for closing said open end; a support; means for mounting said container on said support for swinging movement so that said container can be swung to a normal position in use in which said open end is lowermost whereby the worms within the earth or the like held by said container will seek the lowermost portion of the same adjacent said open end; a resilient finger projecting from said support and engageable with said cover member when said container is moved to said normal position in which the open end thereof is lowermost to retain said cover member in closing position relative to said open end and to releasably hold said container against accidental movement, said finger releasing said container for swinging movement to a position in which the open end is uppermost; and means for holding said container in a position in which the open end thereof is uppermost so that a user may move said cover member to uncover said open end and remove a worm through the same.
